[57] CLAIM

The ornamental design for a receptacle for blood sample analyzing, as shown and described.

DESCRIPTION

FIG. 1 is a top plan view of a receptacle for blood sample analyzing showing our new design;

FIG. 2 is a bottom view thereof;

FIG. 3 is a front elevational view thereof, the rear elevational view being substantially identical;

FIG. 4 is a left side end view of the receptacle shown in FIG. 1;

FIG. 5 is a right side end view of the receptacle shown in FIG. 1;

FIG. 6 is a cross-sectional view taken along the line VI—VI' of FIG. 1;

FIG. 7 is a cross-sectional view taken along the line VII—VII' of FIG. 1;

FIG. 8 is a cross-sectional view taken along the line VIII—VIII' of FIG. 1; and,

FIG. 9 is a cross-sectional view taken along the line IX—IX' of FIG. 1.
